No. 36,997.

Patented June 21, 1904.

UNITED STATES PATENT OFFICE.

JAMES W. CATTY, OF NEW YORK, N. Y.

DESIGN FOR A DOILY OR SIMILAR ARTICLE.

SPECIFICATION forming part of Design No. 36,997, dated June 21, 1904.

Application filed May 19, 1904. Serial No. 208,791. Term of patent 7 years.

To all whom it may concern:

Be it known that I, JAMES WALTER CATTY, a subject of His Majesty the King of Great Britain, residing in New York, borough of Manhattan, in the State of New York, have invented a new, original, and ornamental Design for a Doily or Similar Article, of which the following is a specification, reference being had to the accompanying drawing, forming part thereof.

The figure is a plan view of the doily or similar article.

What I claim as new, and desire to secure by Letters Patent, is—

The ornamental design of a doily or similar article, as shown herein. 15

J. W. CATTY.
